VENTILATOR

Carl W. Olson, Minneapolis, Minn.

Application October 27, 1941, Serial No. 416,706

2 Claims.

(Cl. 98—43)

My invention relates to room ventilation, and has among its objects and advantages the provision of an improved fan unit particularly adapted for kitchen ventilating purposes.

Heretofore kitchen ventilators have been installed in wall openings. Such systems have employed chains or sticks for opening and closing doors in the ventilating system employed as a protection against draft and cold. These systems permit cold to be transmitted or conducted through the relatively large steel surfaces, which are seldom built to such a degree of mechanical perfection as to eliminate back draft.

Of late, ceiling ventilation has become the general idea of kitchen ventilation, with a fan operating behind a grill intake positioned directly over the range, and exhausting through a pipe or duct between the joists to the atmosphere.

Accordingly, an object of my invention is to provide a novel ventilating units designed for incorporation in the wall or the ceiling, in which a novel centrifugal fan or turboblower is employed and designed to operate in an efficient manner, and in which the system employs self-closing shutters which effectively prevent back circulation and open in response to air pressure generated upon setting the system in operation. Novel means are incorporated to protect the motor against accumulation of grease and dirt, with the system so designed as to operate in an exceedingly silent manner.

In the accompanying drawings:

Figure 1 is a sectional view of a ceiling structure illustrating my invention incorporated therein;

Figure 2 is a sectional view of a wall structure illustrating the invention incorporated therein;

Figure 3 is a bottom plan view of the centrifugal fan unit;

Figure 4 is a side elevational view partly in section;

Figure 5 is a sectional view along the line 5—5 of Figure 4; and

Figure 6 is a sectional view along the line 6—6 of Figure 4.

In the embodiment selected for illustration, Figure 1 illustrates the centrifugal fan or turboblower unit 10 installed in the ceiling structure 12. The unit 10 is of such proportions as to permit installation thereof between ceiling joists of usual spacing. An opening 14 is provided in the ceiling face 16 for accommodating an inlet neck 18 of the unit 10, with a horizontal duct 20 connected with an outlet neck 22 of the unit

10 and communicating with a weather hood 24 located exteriorly of the building wall 26.

Referring to Figures 3 and 4, which illustrate the specific construction of the unit 10, the inlet neck 18 is located at the bottom side of a fan or blower housing 28 within which is mounted an electric motor 30. This motor is secured to a washer-like air-deflecting plate 32. The motor 30 extends partly through the opening 10 in the plate 32, and is secured to the plate by set screws 34. Projections 36 depend from the top wall 38 of the housing 28 and serve as mounts for the plate 32. Bolts 40 extend through openings in the plate 32 and are threaded into the projections 36 for fixedly securing the plate, with rubber cushioning washers 42 mounted on the bolts 40 between the plate and the respective boltheads and projections 36.

To the vertical motor shaft 44 is secured a centrifugal fan or turboblower unit 46. This unit comprises a dome-shaped shell, or air-deflecting, 48 opening in the direction of the motor 30 and of such diameter as to permit the motor to project a short distance inside the shell. To the shell 48 are connected radial blades 50 located above the inlet neck 18 and rotating in a plane paralleling the plate 32. The plate 32 is located in close proximity to the upper edges of the blades 50 and functions as a back plate which prevents air from being drawn back into the fan structure from that side.

Figure 3 illustrates the curved contour of the fan housing 28 when viewed axially of the fan unit 46, the diameter of the curvature being such as to provide an air circulating space 52 extending completely about the fan unit 46 and communicating with the inlet neck 18 as well as the outlet neck 22.

Normally closing the outlet neck 22 is a shutter 56 lying against the end 58 of the outlet neck. The shutter 56 is pivotally connected at 60 to the neck 22 and may pivot from its normally closed position to its fully opened position, as indicated in dotted lines. To the shutter 56 is connected a weight 62 so located with respect to the pivotal axis of the shutter as to effectively hold the shutter in its closed position and prevent accidental opening or rattling thereof. In addition, the position of the weight with respect to the pivot axis is such as to have a progressively decreasing closing influence on the shutter as it progresses toward its fully opened position. The shutter opens in response to air pressure generated by the fan unit, and the shutter offers little resistance when in its fully opened position so as

not to obstruct flow of exhaust air through the outlet neck 22.

In Figure 1, the weather hood 24 is provided with a shutter 64 normally engaging an abutment 66 and pivotally connected at 68 with the weather hood for pivotal movement in the same manner as the shutter 56. A weight 70 is attached to the shutter 64 and operates in the same manner as the weight 62.

One end of the duct 20 may be soldered to the outlet neck 22 while the other end of the duct is soldered to a neck 72 on the weather hood 24. A grill 14 extends across the inlet neck 18.

In operation, the ventilating structure is easily installed in a conventional ceiling structure. The centrifugal fan unit 46 operates with positive force and drives a large volume of air through a relatively small duct, which can not be accomplished with the general type of blade fans, such fans requiring relatively large ducts to deliver the exhaust air to the atmosphere. For that reason, the delivery duct and the outside shutter, as well as the inside shutter, may be of relatively small sizes, which greatly reduces the heat transfer areas.

Both shutters are automatic, and the shutters are so balanced as to close against jamb surfaces, thus eliminating objectionable closures wherein shutters operate between the sides of a pipe or opening, the latter constructions requiring such loose fitting as to permit draft and cold air to rush back into the room. The air under pressure from the fan unit opens the shutters to fixed points where they exert the least resistance against the flow of the exhaust air. Thus I provide a draft-proof shutter structure, which works automatically with the operation of the fan and offers very little resistance to the free air flow from the fan.

The fan housing 28 is shaped in such a manner that the centrifugal action of the blower draws the air in through the grill covered opening and distributes the air against the curved sides of the fan housing. Because of the back or air-deflecting plate 32 which is flat and located in a plane normal to the axis of the air inlet opening 18 and intersecting the air outlet opening 22, the air is forced upward along the curved sides of the housing and over the back plate and then through the shutter opening and to the duct 20 for passage to the atmosphere. The curved contour of the fan housing provides a silent flow of the air with greatly increased efficiency. While a large amount of the exhaust air goes out directly through the shutter opening without passing over the back plate 32, the back plate does insure against recirculation of the air through the tendency of the blower to draw air from the rear side.

Figure 2 illustrates the unit 10 mounted vertically in the wall 16. In such an installation, the weather hood 78 is connected with the neck 22 through the medium of a short conduit 80. The weather hood 78 is provided with a shutter

82 corresponding to the shutter 64 of Figure 1. In order to render the shutter 56 of the unit 10 self-closing when the unit is installed vertically in the building wall, a lever 84 is pivotally connected intermediate its ends with the top wall of the neck 22, as at 86, for closing the shutter 56. One end of the lever is provided with a weight 88 and its other end is pivotally connected with a rigid link 90 pivotally connected at 92 with the shutter 56. When the unit 10 is installed in accordance with Figures 1 and 4, the weight 88 is inoperative with respect to closing the shutter. When, however, the unit is vertically installed in accordance with Figure 2, the weight 88 operates to close the shutter when the fan unit is shut down. I prefer to incorporate the weight closing structure of Figures 5 and 6 in all units so that the latter may be installed either horizontally or vertically, thereby eliminating the necessity of manufacturing two specific types of units.

The motor 38 may be electrically connected with wires in a conduit 94 leading to an outlet box 96 provided with a conventional switch 98.

Without further elaboration, the foregoing will so fully illustrate my invention, that others may, by applying current knowledge, readily adapt the same for use under various conditions of service.

30 I claim:

1. A ventilator comprising a housing having an air inlet opening in its bottom wall and an air outlet opening in its side wall, an air deflecting plate having a central opening and secured 35 within the housing between the top and bottom walls thereof, the plate being flat and located in a plane normal to the axis of the air inlet opening and intersecting the air outlet opening, an electric motor extending partly through the 40 opening in the plate with its shaft in alignment with the axis of the air inlet opening, a substantially semispherical shell fixed to the shaft with its open side facing the plate, and blades extending radially from the shell, the upper edges 45 of the shell and blades being close to the plate.

2. A ventilator comprising a housing having an air inlet opening and an air outlet opening, a fan within the housing, a motor for driving the fan, a shutter for the outlet opening hinged at one 50 side of said opening, a weight fixed to the shutter near the hinged edge thereof for holding the shutter closed when the fan is at rest and the housing is in a horizontal position, a lever pivoted between its ends within the housing at 55 the opposite side of the air outlet opening and provided at one end with a weight, and a member pivotally connected to the other end of the lever and to the shutter near the free edge of the latter, the weighted lever being adapted to hold 60 the shutter closed when the housing is in a vertical position with the air inlet opening facing downwardly.

CARL W. OLSON.
